UNITED STATES PATENT OFFICE

99,364

DESIGN FOR A BRUSH

Ray Athol Paisley, Frederick, Md., assignor to Ox
Fibre Brush Company, Inc., New York, N. Y., a corporation of Delaware

Application March 17, 1936, Serial No. 61,672

Term of patent 14 years

To all whom it may concern:

Be it known that I, Ray Athol Paisley, a citizen of the United States, residing at Frederick, in the county of Frederick and State of Maryland, have invented a new, original, and ornamental Design for a Brush, of which the following is a specification, reference being had to the accompanying drawing, forming part thereof.

Figure 1 is a plan of a brush showing my new design, and Fig. 2 is a side elevation of the said brush.

I claim—

The ornamental design for a brush substantially as shown.

RAY ATHOL PAISLEY.
